(57) **CLAIM**

The ornamental design for an egg yolk separator, as shown and described.

DESCRIPTION

FIG. 1 is a top, front, left side perspective view of an egg yolk separator showing my new design;
FIG. 2 is a bottom, rear, right side perspective view thereof;
FIG. 3 is an enlarged front elevation view thereof;
FIG. 4 is an enlarged rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

1 Claim, 5 Drawing Sheets
